UNITED STATES PATENT OFFICE.

WILLIAM E. RAMSAY, OF PERTH AMBOY, NEW JERSEY.

FORMALDEHYDE-GENERATOR.

No. 802,596.

Specification of Letters Patent.

Patented Oct. 24, 1905.

Application filed February 25, 1904. Serial No. 195,246.

To all whom it may concern:

Be it known that I, WILLIAM E. RAMSAY, a citizen of the United States, residing at Perth Amboy, in the county of Middlesex and State 5 of New Jersey, have invented a new and useful Formaldehyde-Generator, of which the following is a specification.

My invention relates to a formaldehyde-generator of a new and convenient construction.

Up to the present time the ordinary formaldehyde-generator has consisted of a reservoir to hold the formalin and a heating arrangement under the reservoir, so as to volatilize 15 the formaldehyde in the solution. There are a number of disadvantages in such a device. For instance, in order to work economically a certain definite amount of formalin should be used for a certain definite area to be dis- 20 infected; but with the apparatus as now in use it is impossible to predetermine the exact amount of formalin to be used, as whatever is in the reservoir the whole of it must be evaporated. Then, again, the apparatus after 25 being cooled first has to be recharged before another operation can take place. It takes considerable time before the volatilization starts, because the whole amount of the formalin in the reservoir has first to be heat- 30 ed to the boiling-point. The formalin contains methyl alcohol, the latter evaporating first on account of its lower boiling-point. This is a decided disadvantage, as experiment has shown that a mixture of formaldehyde 35 with methyl alcohol has a greater germicidal power than formaldehyde alone.

My invention, as I have proved by practical experiments, overcomes all of the difficulties referred to.

40 In the following I have described, with reference to the accompanying drawings, two structures embodying my invention, the particular features thereof being hereinafter pointed out in the claim.

45 Figure 1 is a side elevation of a formaldehyde-generator of large size constructed in accordance with my invention. Fig. 2 is an elevation, partly in section, of a modification adapted particularly for household use.

50 The apparatus illustrated in Fig. 1 comprises a container or reservoir 3 for holding the formalin. In connection with this reservoir 3 is a pump 4, adapted to cause a suitable air-pressure on the formalin for driving 55 the same out of the reservoir through a pipe 5, having a suitable valve 6. A pressure-

gage 7 is connected with the interior of reservoir 3, so as to indicate the air-pressure. A gage-glass 8 is provided on one side of the reservoir 3, having suitable valves 9 9 communicating with the interior of the receptacle, so as to show the amount of formalin within. An opening 10 is provided for pouring the formalin into the reservoir. Pipe 5 through valve 6 is connected with the volatilizer 11, 60 entirely supported from the reservoir by means of a suitable connecting hose or pipe 12. The volatilizer 11 is preferably of spherical shape and is provided with an opening 13, through which the volatilized vapor escapes. 65 The volatilizer 11 is adapted to be held in a suitable frame 14, within which and beneath the volatilizer 11 is situated a suitable heating arrangement or lamp 15.

In the operation of the apparatus the container or reservoir 3 is charged with formalin through the opening 10, which is then suitably closed. The total amount of the charge will be seen on the gage-glass 8. The valve 6 is then closed and the volatilizer 11 heated 70 by means of the lamp 15 or other suitable heating means. The pump 4 is then caused to give a certain pressure within the receptacle 3, the pressure being indicated on the pressure-gage 7. When the pressure has 75 reached a suitable degree, the valve 6 is opened and the formalin is forced through the pipes 5 and 12 into the volatilizer 11, where a very rapid and uniform volatilization takes place, the gas passing out through the 80 opening 13.

In Fig. 2 a similar apparatus is illustrated in which the parts are more compactly combined. In this figure the formalin-container is divided into two parts sealed from each other by means of wall 16, one part 17 being adapted to contain the formalin and the other part 18, in connection with the wick 19, being adapted to act as a burner or heater. In this case the pressure in the compartment containing the formalin is caused by means of a hand-bulb 20, which forces the solution through the pipe 21 into the volatilizer 22 and out through the opening 23 in a manner similar to that already described.

It is obvious that in either of the constructions described only the formalin passing into the volatilizer is heated, that in the reservoir being unaffected by the heat, and as soon as enough formalin has been used to disinfect 110 the particular area desired the lamp can be extinguished and the valve 6 in Fig. 1 turned

off, or in the apparatus of Fig. 2 air-pressure ceases.

It is obvious that the construction of the apparatus may be considerably varied without departing from the spirit of my invention, and I do not restrict myself to the details herein shown and described.

What I claim as my invention, and desire to secure by Letters Patent, is—

- 1. A formaldehyde-generator comprising two independent chambers, one of which is adapted to contain formaldehyde solution, and the other adapted to form a lamp or burner, a volatilizer separate from the formaldehyde-

chamber, a connection between the volatilizer and the formaldehyde-chamber, and means for forcing the formaldehyde solution into the volatilizer whereby the lamp is permitted to heat the solution in the volatilizer without imparting any heat to the solution in the chamber, substantially as described.

In witness whereof I have hereunto signed my name in the presence of two subscribing witnesses.

WILLIAM E. RAMSAY.
